UNITED STATES PATENT OFFICE.

CHARLES KAEPPPEL, OF NEW YORK, N. Y.

DUMPING-WAGON.

SPECIFICATION forming part of Letters Patent No. 287,547, dated October 30, 1883.

Application filed July 20, 1883. (No model.)

To all whom it may concern:

Be it known that I, CHARLES KAEPPPEL, of the city, county, and State of New York, have invented certain new and useful Improvements in Dumping-Wagons, of which the following is a specification.

This invention has reference to certain improvements in dumping-trucks for carrying coal and other materials, for which Letters Patent have been granted to me heretofore, said Letters Patent being dated February 20, 1883.

In the accompanying drawings, Figure 1 represents a side elevation of my improved dumping-truck, showing the two principal positions of the truck-body. Fig. 2 is an end view of the truck-body. Fig. 3 is a plan of the platform of the truck.

Similar letters of reference indicate the corresponding parts.

Referring to the drawings, A represents the platform, that extends from the curved portion of the rear axle-bearings, B, to and over the fifth-wheel c, which latter is supported in the usual manner by the springs on the front axle. The platform A is recessed from the rear axle-bearings, B, forward to such a length as required by the truck-body D, which is hinged by the arms d' to a transverse pivot-rod, d, that is arranged in front of the vertical line passing through the center of gravity of the truck-body, and also in front of the rear axle. The platform A is also supported by the forward-extending horizontal parts of the rear axle-bearings, B. The hinge-connection of the truck-body D is located some distance below the recessed platform, the pivot-rod d' being supported by the bracket-bearings e, which extend downward, and thus facilitate the dumping of the truck-body D, while the close fitting of the body D into the recess of the platform A prevents any pieces of coal or other articles from entering between the platform A and the body D. The truck-body D is locked to the platform A by means of a transverse and centrally-fulcrumed bar, D', that is acted upon by a strong band-spring, f, at one side, and operated by a chain or pivoted connecting-rod, f', one end of which is connected with the fulcrumed lever f''. The other end of said lever f'' is operated by means of a vertical rod, r, which is furnished with a treadle, r', at its

upper end. When pressure is applied to the treadle r', motion is imparted to the lever-bar D' by means of the described mechanism, and the locking-hooks g, which are arranged in opposite direction to each other at or near the sides of the truck-body, are released, and the latter is then swung downward for dumping its load, lifting the front part of the body so that the rear part passes back of the center of gravity and drops down by gravity. To one side of the platform A a rod, m, is pivoted, which is connected at its other end to a bell-crank lever, m', having its pivot at the rear end of the truck-body D. The end-gate D'' is pivoted at its upper end to the body D, and is held in closed position by a centrally-pivoted bar, n, which is guided in the guide-pieces n', and projects laterally at both sides of the gate D'', the latter being provided with a hole, n'', near each end of the bar n, through which the locking-hooks n'', that are attached to the end of the truck-body D, pass. The pivoted bar n engages the locking-hooks n'', and is acted on by a band-spring, n'', when the truck-body is in its horizontal position; but as soon as the latter is inclined the arm of the bell-crank m' operates upon the projecting end of the bar n, raising it and lowering the other end, thus releasing the locking-hooks n'', while the pressure of the load forces the end-gate open, thereby discharging the load, as shown in dotted lines in Fig. 1. The truck-body D is returned to its horizontal position after dumping by means of a chain or chains, l, attached to the front end of the truck-body D, and passed around guide-pulleys l' to a winding-drum, r', the shaft of which turns in bearings of the standards A' in front of the driver's seat s, which is arranged in the usual manner on the front part of the truck-body. One end of the shaft of the winding-drum is provided with a gear-wheel, which is acted upon by another gear-wheel, provided with a hand-crank. By turning the crank of the gear-wheel and imparting motion to the winding-drum the driver can pull the truck-body D from its dumped position back into a horizontal position until the locking-bar D' engages the hooks and secures the body to the platform.

The advantages of my improved dumping-truck are that the center of gravity of the truck-body, instead of being back of the hind

axle, as heretofore, is in front of the same, whereby a better equilibrium of the load and a diminished strain on the locking devices of the truck-body is obtained. In dumping, 5 the truck-body moves along the rounded-off rear axle-bearing into inclined position and opens automatically the end-gate when nearly in lowermost position, so as to quickly dump the load, after which the body is returned into 10 its normal position on the platform by the windlass arrangement described.

I am aware that a treadle and connecting mechanism for releasing the locking-rod of a truck-body have been used heretofore; also, a 15 windlass arrangement for returning the body after dumping into a horizontal position on the platform, and I therefore do not claim these features, broadly.

Having thus described my invention, I claim 2c as new and desire to secure by Letters Patent—

1. In a dumping-truck, the combination of the platform, the hind axle-bearings rounded off above the axle, bracket-arms attached to 25 said platform and extending downward in front of said axle, a transverse rod the ends of which are supported or pivoted in said bracket-arms, the dumping body, downwardly-projecting

arms secured at their upper ends to said body, and connected at their lower ends to said transverse rod, and mechanism for readjusting the 30 body after it has been dumped or tilted, substantially as described.

2. The combination of a platform having fixed downwardly-extending bracket-arms, a truck-body having downwardly-extending 35 arms pivoted to said bracket-arms in front of the hind axle, a rounded-off bearing above the hind axle, a connecting-rod that extends from said bearing toward the end-gate, a bell-crank lever pivoted to the connecting-rod and ful- 40 crumed to the truck-body, an end-gate pivoted at the upper end to the truck-body, a ful-crumed locking-bar that is engaged by the bell-crank lever, so as to be released from the lock- 45 hooks of the truck-body when the body is dumped, substantially as set forth.

In testimony that I claim the foregoing as my invention I have signed my name in presence of two subscribing witnesses.
